ZONED REHEAT FURNACE

Frank Alexander, Jr., West Boylston, Mass., assignor to Morgan Construction Company, Worcester, Mass., a corporation of Massachusetts

Filed Aug. 2, 1967, Ser. No. 657,976
6 Claims. (Cl. 263—6)

ABSTRACT OF THE DISCLOSURE

This invention relates to a furnace for reheating billets, blooms, or slabs (collectively referred to hereinafter as billets) prior to rolling in a rolling mill. The construction of the furnace makes it possible to heat each billet so that there is a controlled, substantial temperature gradient between the leading and tail ends of the billet when it leaves the reheating furnace. The presence of the predetermined temperature gradient makes it possible to have a substantially uniform billet temperature at each roll stand for the entire length of the billet as it passes therethrough.

Background of the invention

Reheating furnaces for heating a succession of billets prior to rolling the billet in the adjacent rolling mill are standard in the industry. In many mills it is acceptable practice to heat the billet throughout its length to the same or substantially the same temperature. For example, if the billet is to be rolled into rod, the required temperature might be 2100° F. If the first pair of rolls to which the billet is fed is immediately adjacent the pushout door of the furnace, a uniform temperature of the billet is satisfactory because the temperature of each instantaneous part of the billet as it passes through the first pair of rolls in the train will be substantially the same, namely 2100° F. If this is the case, then the temperature of each instantaneous part of the rolled product, when passing through the last pair of finishing rolls, will likewise be the same but lower. Thus, with a uniform but decreasing temperature of the product at each of the roll stands throughout the rolling operation, the finished product will have correspondingly uniform metallurgical properties.

In some mill arrangements, however, it is not customary to have the first pair of rolls immediately adjacent the pushout door. Instead, the first pair of rolls may be a substantial distance from the reheating furnace, so that the pushed out billet will be completely out of the furnace before the leading end of the billet is engaged by the first pair of roughing rolls. If it be assumed that the leading end of the billet enters the first pair of rolls at 2100° F., then because of the time that must necessarily elapse before the tail end of the billet reaches the first pair of rolls, the temperature at the tail end may have dropped substantially, perhaps in the order of 100° F. In such case, it can be seen that the effective rolling temperature of each point in the length of the billet will be slightly below the temperature of that immediately preceding. The result is that the leading end of the billet, for example, might be rolled at a temperature of 2100° F. at the first pair of roughing rolls and 1750° F. at the last pair of finishing rolls, whereas the temperature at the tail end of the billet would be 2000° F. at the first pair of roughing rolls and 1650° F. at the last pair of finishing rolls. This being the case, the metallurgical qualities of the finished rod rolled at a changing temperature from one end to the other would obviously be non uniform.

The difficulty just referred to has, of course, been recognized and the desirability of heating the billet so as

2

to present a temperature gradient has heretofore been appreciated. In the existing reheat furnace designs it is difficult to develop a variable pattern of heat along the length of a billet. Normal practice has been to divide burners into groups across the width of a furnace and control the firing rate of each group. This will develop differential heating to a minor degree. The limitation to the degree of differential heating is the effect of radiation and re-radiation from roof, walls, and hearth.

Summary

Applicant's invention is specifically directed to the particular construction of a re-heating furnace that makes it possible to impart to each billet prior to its being pushed out of the furnace to the rolls a temperature gradient of any required degree. Experience will determine the gradient required so that the billet when rolled will present through all points of its length the same temperature at any given roll stand. Thus, if it is desired that the temperature at the final finishing rolls should be 1900° F., the presence of the temperature gradient will result in a temperature of 1900° F. from the leading end to the tail end of the billet when each instantaneous part arrives at the finishing stand.

The furnace that achieves this result includes a novel arrangement of baffle walls located in spaced relation across the furnace width and running longitudinally in the furnace at right angles to the length of the billets. The baffle walls physically divide the furnace into zones and act to contain the heating radiations and re-radiations from the roof, walls, hearth and baffle walls in the area where the heat pattern is required. By varying the number of baffle walls, as many zones may be provided as necessary to give the required temperature gradient. The gradient is developed sufficiently quickly that equalization of the temperature throughout the billet by conduction does not have time to occur before the billet is pushed out of the furnace.

Brief description of the drawings

In the drawings, FIG. 1 is a vertical longitudinal cross section of a reheating furnace showing the depending baffles at the high heat end of the furnace adjacent the pushout door.

FIG. 2 is a section taken on the line 2—2 of FIG. 1 and drawn to an enlarged scale.

FIG. 3 is a fragmentary detail of a vertical section taken on the line 3—3 of FIG. 1 drawn to still further enlarged scale illustrating one construction of baffle.

FIG. 4 is a section on the line 4—4 of FIG. 3 showing details of the wall construction.

Description of the preferred embodiment

Referring first to FIG. 1, the numeral 2 indicates in general a reheating furnace of which the conventional billet receiving end at the right has been broken away. This furnace has a hearth, walls and ceiling indicated at 4, 6 and 8 made in conventional manner of conventional materials. The billets 10 are pushed into the receiving end of the furnace to lie side by side and to be advanced toward the discharge end of the furnace by conventional pusher bars not shown. As the billets advance step by step and side by side through the furnace, they are gradually heated by a plurality of burners 12 located across the vertical intermediate wall 14. By the time the billets have arrived under the low ceiling 16, they will have been heated uniformly from end to end and might be at a temperature in the order of 1900° F. The billets then advance into the high temperature end of the furnace to be brought up to

final temperature before being discharged through the pushout door 18.

The temperature gradient that is developed in each billet is achieved through the use of a plurality of the depending baffles 20 which are illustrated in detail in FIGS. 2, 3 and 4. Each of these baffles is identical with the others so that the description of one will suffice for all. While only two baffles have been shown in FIG. 2, it will be understood that there may be three or four if it is found necessary to create a steeper temperature gradient. As shown in FIG. 2, it will be assumed that the end billet 10, fully heated, is to be pushed out through pushout door 22 through the use of conventional pushout mechanism, not shown. The several burners in the final zone are illustrated collectively at 24 in FIG. 1 and individually at 26, 28, 30, 32, 34, 36 and 38 in FIG. 2. Again the number and capacity of the burners and their location will be dictated by the temperature gradient required. Let us assume that each billet 10 should have a temperature gradient when it leaves the furnace varying from 2100° F. at the leading end to 2300° F. at the tail end. To produce this result, the burners 26 and 28 are set to produce a high temperature, the burners 30, 32 and 34 an intermediate temperature, and the burners 36 and 38 a low temperature. The radiations from burners 26 and 28, for example, reflect from the wall 40 and ceiling 42 and baffle 20 to raise the temperature of billet 10 in Zone A to 2300° F. The burners in Zone B, 30, 32 and 34 will raise the temperature of the intermediate section of the billet to 2200° F., and the burners 36 and 38 in zone C will raise the temperature of the billet to 2100° F. It is obvious, of course, that if the billet were allowed to soak at these temperatures for a substantial period of time, the conductivity of the billet 10 would lessen the temperature gradient. However, by experimentation with the burner temperatures in the several zones, it has been found possible to create in each billet a substantial temperature gradient which will produce a uniform temperature of each instantaneous part of the work at each roll statnd as the work passes therethrough.

The suspended baffle walls which serve to isolate sufficiently the different temperatures produced in each of the zones will now be described. It is to be understood, of course, that each baffle may be made in any convenient way, but the form herein presented has been found relatively simple to install and easy to maintain.

Two longitudinal slots 44 are provided in the roof 44. These slots extend from the wall 6 to the low ceiling portion 16. Above the furnace are a sufficient number of crosswise extending beams 46 to which are attached longitudinally extending members 48 of sufficient strength to carry the load of the baffle walls. In the form shown, there is a number 48 over each of the two openings 44. Depending from beams 48 are a plurality of U-shaped supporting rods 50 which carry one or more members 52 which in turn serve to support thereon refractory bricks 54. The two adjacent members 52, one above the other, are connected in any convenient manner as by an oval loop 56.

The members 52, as seen in FIG. 4, are in the shape of short sections of vertical I-beams with their flanges 53 and 55 acting as means for holding the inturned flanges 57 and 59 of the superimposed refractory members in aligned position in which the cooperating ribs and grooves 61 and 63 interlock.

In assembling the baffle wall, the support rods 50 with the members 52 hanging therefrom are lowered down into the furnace a sufficient distance to permit the builder to place the individual refractory members 54 on the supports 52. The lowermost pie-shaped refractory members indicated at 58 are placed on the supports 52 first, sliding downwardly to the bottom to meet and curve around in the manner shown. Then the horizontal members 60 are dropped in place, interlocking with the members 52 and 75

with each other, thus to provide one unit of the baffle wall.

Each baffle wall unit is indicated by the letter U as can be seen in FIG. 1. As each unit is completed, it is pulled up in place against the underside of the ceiling 42, as shown in FIG. 3, by taking up on the nuts 62 acting on the threaded portion of the U-shaped support rods 50. Where the ceiling slopes as at 64, the upper surfaces of the adjacent refractory units 54 are beveled so as to fit snugly against this part of the underside of the ceiling.

In the foregoing manner, each baffle unit is assembled and pulled up to final position. There is no requirement that the fit of the portion of the baffles within the slots 44 be of a precision character. They merely need to fit comfortably therewithin and pulled up tight enough to prevent the escape of furnace gases and attendant heat.

The vertical dimension of the baffles may be varied to some degree. The greater the vertical dimension, the better the temperatures in zones A, B and C may be maintained without interference from the differing temperatures in the adjacent zones. On the other hand, baffles of greater vertical dimensions will cost somewhat more to install initially and to maintain thereafter.

With the principles of the invention now understood, it will be apparent that the requirement temperatures to be produced in each billet will have to be determined by a certain amount of experimentation with the burners. Once these zone temperatures and burner settings are determined, then billets with the required temperature gradient can be reproduced repeatedly to give the required uniform temperatures at all stands of the subsequent rolling operation. The present invention thus enables the rolling mill to produce a produce of capable of meeting the constantly increasing tolerances now required in the industry.

It is intended to cover all changes and modifications of the examples of the invention herein chosen for purposes of the disclosure which do not constitute departures from the spirit and scope of the invention.

I claim:

1. A reheating furnace having at the discharge end of the furnace a plurality of parallel spaced longitudinally extending baffle walls that depend downwardly from the roof of the furnace to provide zoned heating areas that will be relatively immune from temperatures in adjacent zones, burners positioned in the end wall of the furnace in each zone controllable as to temperature whereby the temperatures in each zone may be increased substantially from one side of the furnace to the other, and whereby the billets subjected to the progressively increasing temperatures in the zones will be heated so as to have a substantial temperature gradient therein extending increasingly from the leading end to the ail end of each billet and whereby each said billet so heated when pushed from the reheating furnace will incorporate such temperature gradient.

2. The furnace as set forth in claim 1 in which each said baffle wall comprises a plurality of individual units arranged side by side thereby to produce a wall capable of isolating said temperature zones from each other.

3. The furnace as set forth in claim 1, in which the baffle walls are constructed of a plurality of depending side by side units hanging from the ceiling and extending from the discharge end of the furnace to meet the sloping part of the ceiling that defines the limit of the high temperature part of the furnace.

4. The furnace as set forth in claim 1, in which the bottom of the baffle walls are more or less on the same level as the burners in the end wall whereby the heat produced by the burners in each zone will be largely confined therein to act on that portion of the billet therebelow to produce the required temperature gradient therein.

5. The furnace as set forth in claim 1, in which each baffle wall comprises a plurality of side by side substantially identical units made of a plurality of refractory

members positioned one on the other, each unit being supported by vertically movable means extending through the furnace ceiling permitting the unit to be lowered below the said ceiling far enough for initial assembly of the refractory members, and means for substantially closing all ceiling apertures above said baffle walls when the walls are raised by said vertically movable means to final proper position.

6. The furnace set forth in claim 5, in which said vertically movable means comprises a depending rod hanging through said ceiling from a support thereabove, a member hanging from said rod having vertically disposed means for receiving and holding thereon a plurality of vertically stacked refractory members whereby said refractory members after being assembled one on the

5

10

15

other may be drawn upwardly by said rod to rest against said ceiling.
